J. J. DESJARDINS

RADIATOR ATTACHMENT

Filed July 5, 1923

Inventor
J. J. Desjardins

By *John Murphy Atty.*

UNITED STATES PATENT OFFICE.

JOHN J. DESJARDINS, OF MARINETTE, WISCONSIN.

RADIATOR ATTACHMENT.

Application filed July 5, 1923. Serial No. 649,714.

To all whom it may concern:

Be it known that I, JOHN J. DESJARDINS, a citizen of the United States, residing at Marinette, in the county of Marinette and 5 State of Wisconsin, have invented certain new and useful Improvements in Radiator Attachments; and I do hereby declare the following to be a full, clear, and exact description of the invention, such as will enable others skilled in the art to which it 10 appertains to make and use the same.

The principal object of the present invention is the provision of an attachment for the radiators of heating systems whereby to 15 moisten the air, equalize the temperature and protect the walls and decorations from dust and dirt.

Other objects and advantages will be apparent and suggest themselves as the nature 20 of the invention is understood.

While the drawings illustrate an embodiment of the invention it is to be understood that in adapting the same to meet different conditions and requirements, various changes 25 in the form, proportion and minor details of construction may be resorted to without departing from the nature of the invention.

Referring to the accompanying drawings forming a part of the application:

30 Figure 1 is a perspective view of the attachment,

Figure 2 is a detail view showing the attachment in vertical longitudinal section and applied to a radiator, and

35 Figure 3 is a detail sectional view on the line 3—3 of Figure 2.

Corresponding and like parts are referred to in the following description and designated in the several views of the drawings 40 by like reference characters.

The numeral 1 designates a radiator such as generally employed in steam and hot water heating systems and is illustrated to demonstrate the application of the invention. 45

The attachment comprises a hood including a top 2 and enclosing walls, such as a front 3, back 4 and sides 5. The back 4 is of greater depth than the front 3 and the

lower edges of the sides 5 incline rearwardly and downwardly. The hood may be of any construction and is preferably of a size to snugly fit the upper portion of the radiator, as indicated most clearly in Figures 2 and 3. An opening 6 is formed in the upper portion of the front 3 and a deflector 7 is disposed opposite the opening to direct the moist air outwardly and downwardly, whereby to insure a more uniform distribution thereof. An opening 8 is also provided in the upper portion of a side and a plate 9 is attached to the outer face of the side in line with the opening 8 and a portion 10 extends downwardly across the opening 8 to provide a baffle. 50

A receptacle 11 disposed within the upper portion of the hood is adapted to receive a quantity of water for evaporation in order to render the air moist or humid. The receptacle 11, as shown, is of the nature 70 of a trough and is supported at one end in the opening 8 and has its inner or opposite end attached to the opposite side of the hood, as indicated at 12. As indicated most clearly in Figures 2 and 3, the receptacle 11 forms supporting means for the attachment and rests upon the top of the radiator. The end of the receptacle projecting through the opening 8 is attached to the plate 9 and projects beyond the same 75 a short distance, as indicated at 11^a to provide a filler whereby to conveniently supply water to the receptacle when required. A hinged cover 13 closes the extension 11^a of the receptacle. 80

The device when applied to the upper portion of a radiator arrests the upward currents of air and deflects the same forwardly and downwardly and away from the wall adjacent the radiator and at the 90 same time renders the hot air moist with the result that injury to walls and decorations is prevented and the air made suitable for respiration.

What is claimed is:

A radiator attachment comprising a hood having an opening in its upper portion, an elongated receptacle disposed within the 95

upper portion of the hood to rest on a radiator and support the attachment, said receptacle having its outer end projecting through and outwardly beyond said opening, a plate exteriorly engaging said hood about said opening and through which the receptacle passes, and said plate having a portion depending below the upper edge of

and into the receptacle and partly across said opening to serve as a baffle.

In testimony whereof I affix my signature in presence of two witnesses.

JOHN J. DESJARDINS.

Witnesses:

THURMAN B. DOYLE,
D. L. REAVEY.
